The ornamental design for a tamper evident lid for container with a locking lid and rim or the like, as shown and described.

DESCRIPTION

FIG. 1 is a top and right rear perspective view of a tamper evident lid for container with a locking lid and rim, showing our new design when in an open position;

FIG. 2 is a top plan view thereof;

FIG. 3 is a bottom plan view thereof;

FIG. 4 is a top and right front perspective view thereof shown when in a closed position;

FIG. 5 is a right side elevational view thereof;

FIG. 6 is a front elevational view thereof; and,

FIG. 7 is a rear elevational view thereof.

The phantom line showing in the figures is for illustrative purposes only and forms no part of the claimed design.
